Application October 6, 1931, Serial No. 567,160

2 Claims. (Cl. 229—4.5)

This invention relates to containers, particularly to those made from spirally wound and overlapped strips, as paper, forming paper bottles or other forms of paper containers.

Containers of various kinds have been made of thin material, which is had in the market in sheet form, as well as in long continuous strips, wound in rolls, for ready use, in the various trades. Considering paper as a cheap and serviceable material from which to make a manufactured and practical container, having a progressively convergent wall, either as the whole side wall of a container, or a portion thereof, particularly as one simulating the form and size of a given bottle, and considering also, that we are to use paper of suitable thickness and quality as it comes in the form of rolls, it is our main object to provide a tapered wall structure to said container, which can be readily manufactured, when produced in large quantities, and which structure will lend itself to the use of strips, spirally wound in overlapping relation, in forming the tapered wall.

It is our further object, in connection with said tapered wall, to provide a form of a contraction or shortening to one edge part of said strips, by way of a series of overlapped plaits, created in the advancing edge part of the strips, as the same are wound in spiral relation upon a convergently tapered mandrel, considering here, not the method of making the bottle, but rather the resultant container structure, so formed and embodied in the tapered wall portion, wherein the overlapped and plaited strips are glued or cemented together.

Such a wall structure may be embodied in a paper bottle made for milk or one having a different tapered portion, where the bottle is to be used for oil or other material.

A further object is to provide such a bottle as will fulfill any or all of the above named objects and at the same time be lighter and much cheaper than the glass bottle, which it is designed to replace. We desire to provide such a paper bottle which can be made automatically, without much handling in the making, and at a cost which will warrant its being thrown away after a single use.

In making such a bottle to be lighter than a glass bottle of a given size, it is our desire to save in the weight item of handling milk, oil, and other bottles, so that more paper bottles of like capacity can be carried, than glass bottles, in a delivery truck, per trip, and being of a shape simulating the glass bottle which it replaces, it will be adapted to fit the carriers now used for the glass bottles.

Another object is to provide a form of paper bottle of the class described, which will afford a substantial and rigid construction fulfilling all of the form and strength requirements now fulfilled by the glass bottle, yet eliminating the breakage factor common to glass bottles, as a cutting danger both to automobile tires and to persons.

A further object is to provide a paper bottle which will particularly simulate the usual form of motor oil glass bottles, having a long tapered neck portion, and having a flat cap or disc closure. In addition we wish to provide a cap closure that is formed by machinery to be fixed in place and is not releasable, once the paper bottle is filled with oil, requiring the cutting off of the bottle top, with its cap, to release the contents of the bottle, thus destroying its use for a refill and at the same time, making the mutilating of the bottle noticeable, if an attempt is made to substitute another and inferior oil, once the bottle of oil is received by a dealer to be sold retail.

A special cheap tool can be provided for cutting off the top of the bottle.

With these and other objects, which will hereinafter appear, our invention resides in certain forms of construction. Various embodiments of our invention are illustrated in the drawings and are hereinafter described and what we claim is set forth.

In the drawings,

Figure 1 is an elevation, partly broken away, showing a finished form of paper milk bottle, embodying our invention.

Figure 2 is a top plan of the bottle shown in Figure 1.

Figure 3 is an elevation, partly broken away, showing the bottle illustrated in Figure 1, but here in an unfinished condition, with dies shown in section, for shaping the ends.

Figure 4 is an elevation, partly broken away, showing a finished form of filled paper oil bottle, with the cap cover secured in place.

Figure 5 shows a perspective view of a fragment of strip as part of a tapered wall structure, wherein the upper edge of the strip is shown contracted or shortened by a series of overlapped plaits.

In the figures, two forms of paper bottles are shown, one form being that of a milk bottle and the other form being that of an oil bottle. Considering first the paper milk bottle, that marked 15, illustrated in Figures 1, 2 and 3, has a wall 16, made up of inside and outside laminated paper 110

strip portions. These wall portions 17 and 18 are formed independent of one another, except that they are cemented together. Each of the portions 17 and 18 is formed of a plurality of overlapping and continuously wound, spiral layers of paper strip 19, wherein the strips overlap one another, so as to provide a multiple thickness of paper to each of the wall portions 17 and 18. According to the width of paper strip used and the amount of overlap for each convolution of the succeeding spiral coils of paper wound on, one can form as thick a wall portion as desired, according to the overlap and number of overlapped windings used, and have as many such wall portions as will give him the thickness of bottle wall required.

There is a bottom disc 20, of paper, having a flange 21, which is curled up to lock the bottle bottom both ways, to fix it therein. The mouth 22, of the bottle is formed with a cap seat 23, and a built-up flange 24, wherein several thicknesses of paper are wound together. The bottle is shown to have a cylindrical portion 25, extending from the bottom disc 20 to the point 26, where the bottle tapers convergently upward, having a reverse curve in vertical section, as shown in Figure 1, and terminates in the neck 27. The tapered portion 28, extending from the point 26, to the neck 27, is made up of tucked-in spiral, overlapping strips, wherein the small, short, vertical markings 28^a, on the figure, represent the multiplicity or series of tucks or overlapped plaits, of the paper strip coils, forming a contraction or shortening of the upper edge portion of the strip to conform to the gradual reduction in the circumference of the tapered portion 28, of the bottle, as we advance toward the mouth 22. A protective coating 29, of any suitable substance, as wax or lacquer, covers the bottle inside and out.

The long oil-bottle 30, shown in Figure 4 is similar in construction to that of the milk bottle, illustrated in Figure 1, except as to its top 31, and the form of the tapered portion 32, of the bottle 30.

The wall 33, of the bottle 30, has a cylindrical portion 34 and a conical portion 35, the upper part of which forms a neck 36, above which is the mouth 37. The cap 38, resting on the seat 39 is secured in place by rolling in the top part 40, of the bottle wall, as at 41. The flanged portion 42, at the mouth 37, of the bottle, is made up of extra windings of paper and is formed by being compressed in dies, as is the flange 24, of the milk bottle 15. While the oil bottle 30, shown in Figure 4, is first formed with an open mouth, it is here shown with the cap 38 fixed in place, as it will be when filled with oil or other material, ready for the market. A protective coating

60

44, of suitable lacquer or other substance, covers the bottle 30, inside and out.

In Figure 5 we have illustrated a strip fragment, such as one from the tapered wall portion 28, and show a series of overlapped plaits 28^a.

80

Tapered wall portions of other containers than those illustrated and described can be similarly formed of strips, having the contracting or shortening of an edge portion formed by creating therein a series of overlapped plaits.

85

Containers formed of coiled strips glued together in spiral relation, and particularly those having tapered portions made in accordance with this invention, are very strong and durable, as well as being light and leakproof, where a suitable adhesive is used. And the compressed formation of the mouth permits of the same kind of handling for filling and capping particularly using a sheet metal cap, either one rolled on or one such as a crown cap, as is done now with glass bottles. Besides, the great stiffness of a bottle embodying our invention makes it reliable in withstanding top pressures attending the use of capping machines, as well as in handling, after being capped. The cheapness with which such paper bottles can be made, permits of throwing them away after one use. When such a form of bottle, as illustrated in Figure 4, is made with a rolled-in top, after filling and capping the bottle for the retail trade, the top can be cut off to discharge the oil, or where a cap shield of rolled-around, sheet metal is used, it can be torn off in the usual way when opening the bottle, as is now done with glass bottles.

90

Inasmuch as changes can be made differing from the embodiments of our invention, as herein shown and described, without departing from the spirit and scope of our invention, we wish to include all changes which come within the purview of the following claims.

115

We claim,

1. In a container, a body wall, a tapered portion to said body wall, said tapered portion being formed of coiled strips, overlapping one another in spiral relation, said strips having that edge part, which is toward the converged end of said tapered portion, contracted or shortened by a series of overlapped plaits.

110

2. A container formed of a body wall, a bottom closure to said wall and a mouth, a tapered portion to said wall, said tapered portion being formed of coiled strips overlapping one another in spiral relation, said strips having that edge part which is positioned toward the converged end of said tapered portion formed of a series of overlapped plaits, so as to contract or shorten said edge to form a converged wall.
